SWITCH PLATE

Lawrence M. Persons, St. Louis, Mo., assignor,
by mesne assignments, to Automatic Control
Corporation, St. Louis, Mo., a corporation of
Delaware

Application May 16, 1936, Serial No. 80,090

11 Claims. (Cl. 200—164)

The present invention relates to a switch plate and, in particular, to one that allows a certain amount of movement of the fixed contact and which will effectively break any weld that may occur when the switch is open.

It is an object of the invention to provide a switch of this kind operable to transmit relatively high currents with a minimum of mechanical power.

10 It is a further object of the invention to provide a switch of such low mechanical power requirements that will break any weld that may be formed when the switch is closed.

It is a further object of the invention to provide 15 a switch plate of this type that will permit a controlled movement of the fixed contact and which, in such movement, will set up internal stresses that will tend to move the contact point in a direction different from that produced by

20 the movement of the moving contact lever.

It is a further object of the invention to provide 25 a device producing such stresses in a direction to peel apart any weld that may be produced.

It is a further object of the invention to provide 30 a switch plate that will set up such stresses, principally about an axis at an angle, preferably 90°, to the axis of the movement of the movable contact plate.

It is a further object of the invention to provide 35 such a switch plate, permitting the described movement of the fixed contact, which will distribute the bending actions so as to avoid permanent deformation.

It is a further object of the invention to provide 40 a switch plate that will permit ready movement of the switch plate with the movable contact to a predetermined point, after which the movement is resisted by the production of an increasing amount of potential energy in the plate until this energy exceeds the resisting force joining the contacts, and causes them to break apart.

It is a further object to provide a switch plate 45 of this kind having preformed bends therein of such nature that, upon a tendency of the material to relieve such bends, no deleterious effect will be produced in the switch.

In the drawing:

50 Fig. 1 is an elevation of the switch, open.

Fig. 2 is an elevation of the switch as the contacts first come together.

Fig. 3 is an elevation of the switch with the contacts in finally closed position.

55 Fig. 4 is a section on the line 4—4 of Fig. 1.

Fig. 5 is a section on the line 5—5 of Fig. 2.

Fig. 6 is a section on the line 6—6 of Fig. 3.

Fig. 7 is a horizontal section on the line 7—7

60 of Fig. 1.

Fig. 8 is a perspective view of the switch plate per se.

The switch plate generally indicated at 10 may be mounted on a suitable base element 11, as desired. This base 11 may be of insulating material. The switch plate 10 is of U-shaped configuration and includes a contact leg 12, a fixed leg 13, and a connecting portion 14. The plate is made of some elastic tempered material, such as bronze, so as to be resilient. The leg 13 is secured to the base 11 by suitable means, such as the rivets 15. A contact element 16, preferably with a curved top surface, is secured to the free leg 12 of the switch plate. An electric lead 17 is connected to the leg 13 of the plate. As 18 is shown, the connecting member 14 is turned up at an angle, preferably a right angle, to the plane of the two legs of the switch plate, and forms a bend B with the leg 12 and a bend B' with the leg 13.

Cooperating with the contact 16 is a contact 18 mounted upon a pivoted switch blade 19. This blade may, if desired, include an insulating portion 20. The entire switch blade is pivoted as at 21 to some fixed part of the device 22, such as a continuation of the base 11. A second electric lead 23 is connected to the blade 19, as is shown.

Beneath the base 11 is a magnet 24 secured to the base by the rivet 15. Adapted to be brought into the field of this magnet is an armature 25 having a depending portion 26, the armature forming a continuation of the switch blade 19. The action of the magnet on the armature provides a snap-action for the switch. Any other type of snap-action could be employed.

In the operation of the device, the movable contact 18 is brought to the fixed contact 16 by movement of the switch blade 19 about its pivot 21. When the switch is open, as shown in Figs. 1 and 4, the leg 12 extends somewhat above the surface of the base 11 and is held in this position by the formed shape of the metal. This lost-motion space is produced by providing the bend B further up on the connecting member 14 than the bend B'. As the switch blade 19 descends, the contact 18 reaches the contact 16, as is shown in Figs. 2 and 5. In this position, no movement has been imparted to the movable leg 12 of the switch plate 10.

Further descent of the blade 19 forces the contact 16 down until the leg 12 rests against the base 11. The latter part of the switch blade motion occurs with a snap-action by the effect of the magnet 24 on the armature 25 of the blade 19. This causes a slight deformation of the leg 12 from its original angular relation to the connecting portion 14. This action may be considered as a pivoting about the axis defined by the bend B between the leg 12 and the connecting

portion 14. The result is that the original angle between these elements is increased. It will be observed that this axis B is at right angles to the pivotal axis 21 of the switch blade 18.

5 When the switch seeks to open, it may be that contacts are welded or otherwise held together. In opening, the switch moves backwardly from the position shown in Figs. 3 and 6 to that shown in Figs. 2 and 5, and finally breaks. In moving 10 from the position of Fig. 3 to that of Fig. 2, the motion is comparatively free of any resistance by the blade itself. The contact 16 may follow the contact 18 with only the resistance of the magnet or snap-action mechanism. This permits the switch to get a "running start" before it begins to break the weld. The amount of this running start is determined by the clearance between the leg 12 and the base 11. If the weld is not broken by the time the switch reaches the 15 position of Fig. 2, a further withdrawal of the contact 18 lifts the contact 16, which will tend to pivot the leg 12 about its axis B. This pivotal action is resisted by the structure of the metal itself, since any movement of the leg 12 relative 20 to the connecting portion 14 produces a deformation of the switch plate, owing to its inherent resiliency. The switch plate 10 will yield and permit lifting of the leg 12 until sufficient resistance is produced in the nature of potential energy 25 stored up in the switch plate to be greater than the strength of the weld joining the contacts.

The movements in the switch plate as the contact 16 follows the contact 18 may be analyzed into two main groups. The first group consists 30 in the pivotal movement of the leg 12 about the connecting portion 14, and a division of this with pivotal movement of the connecting portion 14 about the fixed leg 13. This group of movements is about the axes B and B', and it permits 35 the vertical lifting of the contact 16. As the contact 16 lifts, it seeks to bend the leg 12 upwardly toward the connecting portion 14 about the axis line formed by the junction of said leg and said portion. This bending action is resisted by the inherent resiliency of the plate 10, 40 and resolves itself, within the leg 12 and the portion 14 into opposite forces, the one in the leg acting downwardly to force the leg counterclockwise in Fig. 4, and the other in the portion 14 acting outwardly to force the portion clockwise. 45 This latter is necessarily transmitted through the portion 14 to its connection with the fixed leg 13, and, in turn, tends to unbend the portion 14 about the said leg 13. The result is that the lifting 50 of the contact 16 resiliently further bends the leg 12 about the portion 14, and resiliently unbends the portion 14 about the leg 13. This action, being substantially equal and opposite, overcomes the effect of the metal's tendency to 55 right itself from the two bends. In other words, by normal fatigue, metal tends to remove any bends. This tendency would be aggravated by the pivotal action of the arm 12 about the portion 14 in the position of Fig. 6 (or by the opposite movement if the portion 14 were turned down instead of up, as it may be). With an equal and 60 opposite bend in the other leg, this aggravating effect is nullified. Even without it, however, there is a normal tendency of deformed metal to 65 straighten out. In the present device, even if the bends B and B' straighten, since the plate is homogeneous, and the bends alike, they will operate together, and the only result will be a change in the relative position of the portion 14, with no change in the position of the contact 12.

This is an important feature of the invention, since, in previous switches, having no compensating bends, there have occurred prohibitively serious displacements of the contact after the passage of only a few weeks.

5 Since these two bending actions of group one are substantially the same, a detailed analysis of one will suffice for both. Although this group relates to the lifting of the contact 16, it also has a lateral force component. During the lifting of 10 the leg 12 about its axis of bend with the portion 14, the contact 16 moves in an arcuate path about said axis. As shown, the axis of this travel is at a right angle to the axis of travel of the movable contact 18, although the invention is 15 not limited to this exact angle. In travelling in such an arcuate path, the contact 16 remains at a constant distance from the bend. However, the travel of the contact 18, as seen in Figs. 4-6, 20 is in a plane coincident with the arc at only one point. As the contact 18 lifts, it becomes more distant from the bend, resulting in drawing away from the contact 16. In other words, the contact 16 is, in effect, drawn laterally from the contact 18, and, at the same time, is rocked relative thereto, resulting in a peeling action. This combination of actions is effective in tending to 25 break away welds between the contacts.

In recapitulation of the movements of group one, they may be said to include the following: 30 (1) the running start effect, (2) the uplifting effect distributed between the two horizontal bends between the respective legs and the connecting portion, which uplifting effect stores an increasing amount of resistant potential energy 35 in the plate that tends to break the contacts, and (3) the laterally acting forces resulting from the arcuate path of travel of the legs about their bends that draws the contact 16 sideways from and across the surface of the contact 18, and 40 rocks it thereon.

The movements of group two take place about 45 an axis through the connecting portion 14. As heretofore noted, and referring to Figs. 4-6, the contact 16 travels in an arcuate direction 50 about its bend, whereas the contact 18 travels, as respects these views, vertically. If the bend between the leg 12 and the portion 14 were unmovable, the entire stress of the lateral pull by the moving contact 16 would have to be absorbed 55 in tension in the leg. However, it is desirable that provision be made to avoid this. In the present structure, the resiliency of the connecting portion permits it to bend about an axis that may be considered as being the axis of the U. 60 This permits the contact 16 to move toward the pivotal axis 21, or away from it. However, this movement is resisted by the inherent resilience of the connecting portion, and potential energy of resistance to bending—or righting energy—is 65 stored in the portion 14 in an amount increasing as the bend increases. This righting energy produces lateral forces seeking to break the contact 16 from the contact 18, as will be evident. These lateral forces cooperate to peel the contact 16 70 from the contact 18.

It will be understood that these various forces work together, so that the final action is a resultant of all of them. The plate may be designed to leave any of them out, but it is preferable 75 that they all are present. The particular angle between the portion 14 and the legs is immaterial, and a different angle merely changes the direction of the forces of group two. The direction of the axes of bend is most efficient at 90° 75

to the axis 21, but the device will operate at other angles. The axis of the movements of group two is not necessarily coincident with the U-axis, since, in any event, it produces a component thus coincident, and only changes the distribution of the forces.

It is to be observed, further, that these various forces are produced by the plate itself. They could be produced by outside spring means and 10 separate pivots, but only at the cost of simplicity, efficiency, and cheapness. It is immaterial which way the portion 14 extends relative to the legs, whether upward or downward, since the effect is the same for both. The plate is flexible, and 15 yields with comparative freedom to the movements of the contact 18. In so yielding, it sets up these internal stresses acting in the directions noted that peel the contacts apart instead of pulling them apart. Such peeling reduces the 20 energy required for the separation, and yet there is provided a switch that can carry a high electrical load. Hence, it is of great value in such 25 applications as thermostats, wherein the expanding element has low mechanical power that must control a high current circuit.

In the claims to follow, the expression "planar development" is used in its technical sense to mean the imagined bending of one surface, without stretching any one element, to fit upon a 30 plane.

What I claim is:

1. In a switch device, a base, a switch plate comprising a resilient element U-shaped in planar development, one leg of which is secured to the base, a contact on the other leg, and the connecting portion being turned up at an angle to said legs, said connecting portion extending outwardly from the secured leg, laterally, and inwardly to the other leg, so as to extend outwardly 40 in the same direction from both legs.

2. In a switch device, a base, a switch plate comprising a piece of resilient material of U-shape in planar development, one leg of which is secured to the base, a contact on the other leg, 45 said other leg being spaced from the base, and the connecting portion being bent at substantially a right angle to the legs, and extending outwardly from the secured leg, laterally, and inwardly to the other leg.

3. In a switch device, a base, a first contact pivotally mounted for movement to operate the switch, a second contact, a support for the second contact, said support including a first part upon which the contact is mounted, a second part supporting the first part for movement of the first part generally in a first plane, said plane being parallel to the pivot axis of the first contact, and a third part supporting the second part for movement in a plane at an angle to the first plane.

4. In a switch device, a base, a resilient switch plate, a contact, means mounting the switch plate on the base, said plate having a portion resistingly movable generally in a plane intersecting the base, and a portion resistingly movable in a plane parallel to the base, the contact being mounted on one of said portions, which portion is in turn supported by the other portion.

5. In a switch, a resilient switch plate U-shaped in planar development, the bight portion of which is turned out of the plane of each leg, a base, means connecting one leg of the plate rigidly to the base, the other leg being free, whereby said

other leg may move relative to the fixed leg, and a contact on said free leg.

6. In a switch device, a resilient switch plate U-shaped in planar development, the bight portion of which extends outwardly from one leg, laterally, and inwardly to the other leg, a base, means connecting one leg of the plate rigidly to the base, the other leg being free, a contact on said other leg, the connecting portion between said legs being bent at an angle to the legs, a 10 switch lever having a contact adapted to close with the contact on the plate, said lever being pivoted about an axis parallel to the legs of the plate.

7. In a switch device, a base, a contact, means 15 supporting the contact for resiliently resisted displacement substantially in a first plane, means supporting the first supporting means for resiliently resisted displacement substantially in a second plane at an angle to the first plane, and 20 means supporting said second supporting means for resiliently resisted displacement.

8. In a switch device, a base, a contact, means supporting the contact for resiliently resisted displacement in a plane perpendicular to the base, 25 a second means supporting the first supporting means for resiliently resisted displacement in a plane substantially parallel to the base, and a third means supporting the second supporting means for resiliently resisted displacement in a 30 plane perpendicular to the base.

9. In a switch device, a base, a contact, means supporting the contact for resiliently resisted displacement in a first plane perpendicular to the base, a second means supporting the first 35 supporting means for resiliently resisted displacement in a second plane substantially parallel to the base, a third means supporting the second supporting means for resiliently resisted displacement in a third plane perpendicular to 40 the base, and a second contact, means movably joining the second contact to the base for relative movement between them in a plane perpendicular to the base but at an angle to the three previously mentioned perpendicular planes. 45

10. In a device of the kind described, a first contact, a base, a homogeneous resilient metallic element U-shaped in planar development, the bight portion extending outwardly from one leg, laterally, and inwardly to the other leg, one leg 50 of which is secured to the base and the other leg of which resiliently supports the first contact above the base, the connecting portion between said legs being bent at an angle thereto, a magnet adjacent the base, a movable switch blade, a 55 second contact on said blade adapted to close with said first contact, an armature on said blade adapted to come into the field of the magnet as the switch approaches closed position, and said magnet thereupon drawing the armature and 60 both contacts until the first contact rests on the base.

11. In a switch device, a base, a switch plate comprising an element U-shaped in planar development, having resilient legs, and a connecting 65 portion turned at an angle to be out of the plane of both of said legs, one of the legs being secured to the base, and a contact on the other element, and said connecting portion extending outwardly from one leg, laterally, and inwardly to 70 the other leg.

LAWRENCE M. PERSONS.
